Primary Examiner — Melody N Brown(74) *Attorney, Agent, or Firm* — BROOKS KUSHMAN P.C.(57) **CLAIM**

The ornamental design for a front end of motor vehicle as shown and described.

DESCRIPTION

FIG. 1 is a front elevational view of a front end of motor vehicle showing my new design;

FIG. 2 is a front and right side perspective view thereof;

FIG. 3 is a right side perspective view thereof;

FIG. 4 is a top plan view thereof; and,

FIG. 5 is a right side elevational view thereof.

The claimed design is indicated by the relatively dark portions in the figures. The de-emphasized and relatively light portions form no part of the claimed design.
